United States Patent Office.

JOSEPH H. DULL, OF MANSFIELD, OHIO, ASSIGNOR TO BLYMYER, DAY & CO., OF SAME PLACE.

Letters Patent No. 105,055, dated July 5, 1870.

IMPROVED TREAD-POWER.

The Schedule referred to in these Letters Patent and making part of the same.

To all whom it may concern:

Be it known that I, JOSEPH H. DULL, of Mansfield, in the county of Richland and State of Ohio, have invented certain new and useful Improvements in Tread-Powers; and I do hereby declare that the following is a full, clear, and exact description thereof, reference being had to the accompanying drawing making part of this specification, and to the letters of reference marked thereon, like letters indicating like parts wherever they occur.

To enable others skilled in the art to construct and use my invention, I will proceed to describe it.

My invention relates to tread-powers, and

The invention consists in a novel construction and arrangement of the gearing, and also in a device for taking up the slack in the endless belt, thus compensating for the wear in the same.

Figure 1 is a perspective view of the tread-power complete;

Figure 2 is a transverse vertical section of the same, through the center of the gearing; and

Figures 3, 4, 5, and 6, are views of portions, shown in detail.

In constructing my improved tread-power, I provide a frame, A, of the usual style, with an endless belt, C, mounted therein, as is customary in this class of machines.

At the front end of the machine I locate a transverse shaft, B, having secured rigidly to it two sprocket-wheels, D, as represented in fig. 2.

The form of these wheels is shown clearly in fig. 5, they being provided with sprockets or projections, e, each having a notch, f, in its outer end, into which the joint-rods a of the endless belt C fit, these sprockets being located at distances from each other exactly equal to the distances apart of the rods a.

This shaft B, with its wheels D, is so located that the endless belt, at the front end of the machine, will bear upon and pass around the wheels D, so that, as the belt C is moved, it will impart motion to the wheels D, and thereby to the shaft B.

Upon this shaft B, just outside of the frame, I secure a cross-bar, F, which is made strong and rigid on the shaft, this bar thus forming two radial arms, as shown in fig. 2.

Each of the arms, near its outer end, has a journal, o, projecting from its outer face; and on each of these journals I mount loosely a spur-wheel, I, these latter gearing into an internally-ganged or toothed circular rack, E, which is bolted firmly to the side of the frame A, so as to be fixed and stationary.

Upon the outer end of the shaft B I then mount loosely a band-wheel or pulley, L, this wheel L having its hub made to project inwardly between the wheels I, there being a pinion, H, formed on or at-

tached to this inner end of the hub, into which the wheels I gear, as shown in figs. 1 and 2.

By this construction and arrangement of parts it follows that, as the belt C is moved, the shaft B, with its arm F and the wheels I, are made to revolve; and the latter, by gearing into the circular fixed rack E, are made to rotate on their journals o, and they, in turn, impart motion to the pinion H, which, being fast to the band-wheel L, causes it to rotate also, the direction in which the various parts move being indicated by the arrows in fig. 1.

The belt C is mounted on small wheels or rollers, n, secured to the ends of the joint-rods a, and these rollers travel on a rail at each side of the frame, both above and below, as is usual in this class of machines.

At the rear end of the machine I provide a segmental or curved iron rail, T, of the form shown in fig. 6, for the wheels n to run on, this curved rail being formed with slotted flanges, t and m, by which it is bolted fast to the frame, in such a manner as to form a continuation of the track from the upper to the lower rail, as shown in fig. 1.

By means of these slots, which may be made either in the part T or in the frame to which it is attached, the pieces T may be adjusted, to compensate for any wear in the joints of the belt C, and keep it at the proper tension.

By this method of constructing and arranging the various parts of the machine, I am enabled to produce a very efficient and complete tread-power, adapted to all the purposes and uses for which such machines are used.

By the use of the planet-wheels I, and the circular rack E, the shaft B and the pinion H are relieved of the radial thrust or pressure, and, consequently, of the friction which exists with ordinary spur-gearing where the wheels have a bearing on one side only, and thus the power is applied to a better advantage, and more efficiently utilized.

Having thus described my invention,

What I claim is—

1. A tread-power, having two or more planet-wheels, I, secured to its driving-shaft, and arranged to operate substantially as described.

2. The combination of the shaft B with the planet-wheels, mounted on arms rigidly attached thereto, the stationary rack E and the pinion H mounted loosely thereon, all constructed and arranged to operate substantially as described.

3. The adjustable segmental track T, arranged to operate substantially as set forth.

JOSEPH H. DULL.
